UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

DUMP-CAR DOOR AND LOCKING MEANS THEREFOR.

Application filed May 2, 1925. Serial No. 27,364.

My invention relates to improvements in dump car doors and locking means therefor.

An object of this invention is to provide a simplified and improved dump door and to especially adapt the same for use with a simple door locking device.

It is also an object of the invention to utilize embossments formed integrally with the door plate instead of using separate door braces for rigidifying purposes and to adapt the same for use with door locking means.

Another and more specific object of the invention is to utilize a bell crank type of lever for closing the door whereby the door may be closed and locked from the side of the car.

Furthermore my invention resides in certain other features and details of construction such as will be hereinafter more fully pointed out and claimed.

In the drawings forming a part of this specification Figure 1 is a transverse sectional view of a portion of a dump car of the so-called W-type, showing in elevation my improvements in connection therewith. Figure 2 is an elevational view of the dump door shown in Figure 1 detached from the car. Figure 3 is a side elevational view of a portion of the car as shown in Figure 1. Figure 4 is a sectional view taken through the door and on a line corresponding substantially to a line 4-4 of Figure 1. Figure 5 is a fractional sectional view of a portion of the door showing the outer locking arrangement and taken on a line corresponding substantially to a line 5-5 of Figure 1. Figure 6 is a sectional view taken through the door on a line corresponding substantially to the line 6-6 of Figure 1. Figure 7 is a fractional sectional view taken through the door on a line corresponding substantially to the line 7-7 of Figure 1.

In said drawings, 10 denotes one of the side walls of the car, 11 one of the side stakes, 12 one of the channels employed to make up the girder center sill of well known form, and 13 a longitudinally extending reinforcing angle member for the side wall 10 of the car.

As customary in the W-type of car, a central transversely extending ridge is formed as by the ridge sheet 14, it being understood that there are four hoppers in the car, two

on each side of the center sill and arranged in pairs transversely of the car. Each of such hoppers is defined by a sloping hopper sheet 15, a vertical inner side hopper sheet 16, and an outside hopper sheet 17, the latter sloping inwardly towards the longitudinal center line of the car and having its margin 60 reinforced by a plate 117.

Each discharge opening, in the type of car shown in the drawing, is adapted to be closed by a sheet metal door 18, which is preferably flanged at its margins so as to provide a top horizontally extending flange 20, inner side flange 21, and outer side flange 22, and at the free edge of the door the door plate is pressed in the form of a Z as indicated at 23, said flanges 20, 21 and 23 being 70 pressed outwardly in the same general direction from the main plane of the door, while flange 22 is pressed inwardly from the main plane of the door. Said door 18 is pivotally attached by suitable hinge braces 75 24-24 to the brackets 25-25 carried by the lower edge of the transversely extending ridge sheet 14 which is suitably reinforced by means of an angle member 26. The hinge braces 24-24 may consist of heavy strap 80 members which extend from the hinge end of the door for a considerable distance towards the free edge thereof. Adjacent the hinge edge of the door, and in parallelism therewith, a corrugation 27 is formed in the 85 door which serves to reinforce and rigidify the door in a direction at right angles to the hinge braces 24-24. Extending in the same general direction as the braces 24-24 are corrugations 28 and 29, which are formed 90 adjacent the respective side edges of the door and pressed outwardly from the main plane of the door, the corrugations preferably being formed with flat portions as indicated at 128 and 129, respectively, for a purpose 95 hereinafter described. Intermediate said corrugations 28 and 29 another corrugation 30 is formed, which is preferably pressed inwardly or in the opposite direction to the first named corrugations.

The door is adapted to be maintained in closed position by means of a bell crank or angular lever A, which is pivotally mounted intermediate its ends on the door, and formed with arms of varying length. Co- 105 operating with the respective arms of the

lever member A, are shouldered brackets B and C, which are respectively secured to the side hopper walls 16 and 17. Said lever member A is pivoted adjacent the inner side 5 wall of the hopper, on corrugation 28, by means of a bolt 31 the head of which is contained within the corrugation 28, the pivot being disposed near the junction of the arms of the bell crank lever, the arrangement of 10 the pivot being such that the short arm 32 depends substantially vertically toward, and slightly beyond the free edge of the door, whereas the long arm 33 is extended substantially horizontally towards the side of 15 the car and beyond the outer side edge of the door. Due to the weight of the longer arm 33, the lever is adapted to automatically assume its normal locking position as shown in Figure 3. To lock the door the 20 respective arms of the lever seat behind shoulders 34 and 35 respectively formed on the members B and C, the lever being displaced from its normal position during the door closing operation by the short arm 32 25 engaging and riding upon an angularly disposed surface 36 formed integrally with the bracket member B, said surface 36 being so formed that the arm 32 will ride mainly on a beveled projection 37 near the lower end 30 of the surface 36 until such time as the arm 32 passes the shoulder 34, and engages with the said shoulder 34 at the extreme end thereof, where it is flared slightly as indicated at 38. The surface 36 is of triangular form and the vertex of said triangle indicated at 39 is set back from the lower beveled portion 37, and therefore the arm 32 35 is always free to engage mainly with the beveled portion 37.

40 Adjacent the outer wall of the hopper the arm 33 of the member A engages behind the shoulder 35 of the bracket member C. Due to the variation in the length of the respective arms, it is evident that the inner end 45 of the bar will always be the first to engage, and the length of lever which is afforded by the arm 33 enables the exercise of considerable force by an operator in closing the inner end of the door from the side of the 50 car. It will be noted that the bracket member C lies at an angle from the vertical due to the inclination of the side hopper wall toward the center of the car and in order to eliminate unnecessary friction during the 55 opening movement of the door that portion of the bracket which forms the shoulder 35 is inclined or offset as shown at 135 relatively to the main body of the bracket and to the inclined hopper sheet, and is thus 60 brought substantially tangent to an arc described by the lever at the commencement of the unlocking movement of the bar. The bell crank lever A is spaced outwardly from the plane of the door by the corrugations 28 65 and 29, which function as runways for the

respective arms to slide upon. In order to stabilize the lever the same is mounted on a Z-shaped bracket 40 secured to corrugation 28 thereby providing for the placing of pivot 31 in double shear. The arm 32 which is extended outwardly beyond the free edge of the door and engages with the Z-shaped flange 23, is maintained against outward movement by a bracket 41 secured to the door. Adjacent the side edge of the door 75 the arm 33 is adapted to be guided by a member 42, secured to the door by rivets disposed below the bar and is also secured above the said bar by a bolt 43 which also serves as a fulcrum for a locking cam 44, which is 80 adapted to be swung in the path of the arm 33 to lock the same in position. The fact that the outer flange 22, at the side edge of the door, is turned upwardly and away from the door locking mechanism permits 85 free access of the operator to the locking arrangement, and also provides for an efficient door seal between the door and the side wall 17 of the hopper. In order to permit the door flange 22 to lie between the 90 hopper side wall 17 and the bracket C the latter is offset as indicated at 45.

The arrangement for locking the door is thus very simple as the operator stands at the side of the car and pushes the door to 95 closed position, a push pole pocket 46 being provided on the door to receive the end of a pole, said pocket being secured to the front marginal reinforcement 23 of the door as at 47, and to the main door plate 100 as at 48.

In operation, in order to close the door, the operator may stand at the side of the car and kick or push the door to closed position. As the door approaches the closed 105 position, the inner arm 32 of the bar engages the tapered face 37 of the bracket member B, which serves to depress the inner end of the bar, and raise the outer end of the bar. Continued movement of the door 110 in a closing direction finally allows the bar to clear the tapered face 36, and automatically move to locked position, or, if necessary, the operator from a position at the side of the car, may bear down on the outer 115 end of the bar and wedge the door to a fully closed position. In releasing the load in the car the cam 44 is moved out of engagement with the arm 33, and the said arm lifted upwardly to the position indicated by 120 dotted lines in Figure 2, when the respective arms of the lever A will be released from their corresponding brackets and the door will open.

The arrangement of having movable door 125 locking means adapted to directly engage the reinforcing corrugation on the door is of great advantage as it is conducive to strength with light weight, and results in economy through the elimination of parts. 130

I am aware that it is old in the art to use corrugations for reinforcing car doors, but hitherto where such a system of door reinforcing has been used it has been necessary 5 to attach heavy beams or auxiliary stiffening members to the door in order to ultimately transmit the weight of the door and lading to the car structure, and the advantage secured by the saving in weight derived 10 by the use of the corrugations has thus largely been nullified by the additional parts introduced, and therefore direct engagement between a door locking member and a corrugation in the door, such as I have provided, results in great economy. It will 15 be noted that the door retaining lever A engages only the outer corrugations 28 and 29, and the purpose of this arrangement is to ensure that the load on the entire door 20 will be concentrated on the lever member A adjacent the respective shouldered brackets B and C. In the design of door, as shown, the margins at the hinge end of the door and the free edge of the door, which 25 are respectively reinforced by corrugation 27, and marginal Z-shaped rigidifying member 23, receive the load carried on the central part of the door through the medium of the door hinge braces 24—24 and the central corrugation 30, and transmit the load 30 to the corrugations 28 and 29, and thereby to the brackets B and C, the corrugation 30 being turned in the opposite direction from the side corrugations 28 and 29, for the purpose of preventing the door buckling, and 35 ensuring the transmission of the load on the lever A to its ends, the arrangement permitting the use of a lighter locking bar since if the load were transmitted to the 40 central position thereof a much stronger and heavier bar would be necessary to resist the excessive bending strain thus imparted to it.

While I have shown and described a preferred embodiment of my invention it is 45 understood that the same is merely illustrative and I contemplate all constructions which come within the scope of the claims appended hereto.

What I claim is:

50 1. In a dump car, the combination with a swinging door; of an angular lever pivotally mounted on said door and having the arms thereof extended beyond the door; and means on the car adapted to engage the respective ends of the said lever to maintain the door in closed position.

55 2. In a dump car, the combination with a swinging door having a reinforcement adjacent its free edge; of an angular lever pivotally mounted on said door, one arm of the said lever engaging with the reinforcement adjacent the free edge of the door and the other arm of the lever extending beyond the side edge of the door; and means on the car structure co-operable with the respective

arms of the lever to maintain the door in closed position.

3. In a railway car, the combination with a dumping door; of a locking bar pivotally mounted intermediate its ends on the door; means on the car co-operable with the respective ends of the bar to maintain the said door in locked position; and means formed integrally with the door adapted to space the bar from the door, said means constituting runways for the bar. 75

4. In a railway car, the combination with a dumping door; of a locking lever pivotally mounted on the door to swing substantially in the plane of the door, said lever being extended beyond the door; a corrugation pressed in the door and extending in a plane substantially perpendicular to the said lever, said corrugation operating to space the lever from the door; and means on the car structure adapted to engage the projecting end of the bar to lock the door in closed position. 85

5. In a railway car, the combination with a dump door; of a plurality of hinge beams extending from the hinged edge of the door for an appreciable distance towards the free edge of the door; of a reinforcement extending adjacent the hinged edge of the door; a reinforcement extending along the free edge of the door; corrugations extending between the said respective reinforcements, said corrugations being disposed adjacent the side edges of the door and pressed outwardly beyond the plane of the hinge beams; a pivotally mounted beam member on the door, said member being adapted to bear on the last named corrugations; and means carried by the car and co-operable with the respective ends of the beam member to maintain the door in locked position. 95 100 105

6. In a railway car, the combination with a dumping door; of a locking bar pivotally mounted on the door, said bar being spaced outwardly from the plane of the door; corrugated reinforcing means formed in the door plate adapted to maintain the bar in spaced relation to the door, said corrugated means being disposed adjacent the side edges of the door; other corrugated reinforcing means pressed in the door plate in the direction substantially perpendicular to said first named corrugated means; and means on the car structure adapted to engage the respective ends of the bar and maintain the door in closed position. 110 115 120

7. In a dump car, the combination with a dump door; of a series of corrugations formed in the door and extending from the hinged edge of the door towards the free edge thereof; a locking bar pivotally mounted on one of said corrugations, said bar being extended across the plane of another of said corrugations and engageable therewith; and means on the car adapted to engage the 125 130

- said bar adjacent the last named corrugation.
8. In a dump car, the combination with a dump door; of a series of rigidifying corrugations extending outwardly from the door; locking means pivoted on the door and bearing on said corrugations; and means carried by the car adjacent the door co-operable with the said locking means for locking the door in closed position.
9. In a dump car, the combination with a dump door; of a reinforcement formed integrally with the door along the free edge thereof; a lever pivotally mounted on the door and extending beyond the free edge of the door, said lever being adapted to engage the reinforcement along the free edge of the door; and means on the car structure co-operable with the said lever to maintain the door in closed position.
10. In a dump car, the combination with a dump door; of a reinforcement of Z shape extending adjacent the free edge of the door; a lever pivotally mounted on the door and extending beyond the free edge of the door and in engagement with the aforesaid Z-shaped reinforcement; and means on the car structure co-operable with said lever to maintain the door in closed position.
11. In a dump car, the combination with a dumping door; of a bar pivotally mounted on said door, said bar extending beyond the edges of the door; embossments formed in the door plate, said embossments being adapted to space the bar from the main plane of the door; and means on the car structure co-operable with the projecting ends of the bar to lock the door in closed position.
12. In a dump car, the combination with a dumping door, said door having an upturned side marginal flange; a bar pivotally mounted on the door to swing in the main plane of the door; a shouldered bracket secured to the car side adjacent the side edge of the door, said bracket having a portion thereof spaced outwardly from the car side to permit the flange of the door to lie between the said bracket and the car side when the door is in closed position, said shoulder on the bracket being adapted to engage with the said bar to lock the door in closed position.
13. In a railway car, the combination with the center sill and side wall of the car; of a hopper extending from the center sill to side wall of the car, said hopper including a transversely extending door hinged adjacent its upper edge on an axis extending transversely of the car; and means for locking said door adjacent the said center sill and at the side of the car, said means including an angular lever pivotally mounted on the door, and brackets co-operable therewith, one of said brackets being mounted adjacent the center sill of the car and the other of said brackets adjacent the side wall of the car.
14. In a railway car, the combination with the center sill and side wall of the car; of a hopper extending transversely of the car, 70 said hopper being defined by a longitudinally extending sloping hopper sheet, inner and outer side walls, and a swinging door extending on an axis transversely of the car, said outer wall sloping downwardly and 75 inwardly from the vertical towards the longitudinal center of the car, a bell crank lever pivotally mounted on the door, said bell crank lever having arms of different lengths, the longer of said arms extending outwardly 80 beyond the sloping outer wall and the shorter of said arms being co-operable with the free edge of the door and extended outwardly beyond the same; and a shouldered bracket on the car structure co-operable with 85 said short arm of the lever to lock the door in closed position.
15. In a railway car, the combination with the center sill and side wall of the car; of a hopper extending transversely of the car, 90 said hopper being defined by a hopper sheet sloping longitudinally of the car from the center sill of the car towards the side wall of the car, an inner side wall, an outer side wall and a swinging door hinged on an axis 95 extending transversely of the car, said hopper having the outer side wall sloping downwardly and inwardly from the vertical towards the longitudinal center of the car; a bell crank lever pivotally mounted on said door, said bell crank lever having arms of different lengths, the longer of said arms being extended outwardly towards the side edge of the door adjacent the side wall of the car and the shorter of said arms extended 100 towards the free edge of the door; a shouldered bracket on the car structure cooperating with the shorter of said arms for locking the door in closed position; and a locking member acting on the longer of said arms 105 to lock the bell crank lever in position when the door is closed.
16. In a dump car, the combination with a hinged door having corrugations extending from the hinged end towards the free 110 edge thereof; of movable door supporting means adapted to directly engage said corrugations to support the door.
17. In a dump car, the combination with a hinged door having rigidifying means including a rigidifying corrugation formed therein; of a movable door supporting member adapted to engage the corrugation on the door to support the door in closed position, said supporting means being adapted 115 to engage the said corrugation intermediate the ends thereof.
18. In a dump car, the combination with a metallic door; of an embossment formed in the said door, said embossment having a 120
- 130

flat portion; and movable door supporting means co-acting with said flat portion of the embossment.

19. In a railway car, the combination with the center sill and side wall of the car; of a hopper extending transversely of the car, said hopper being defined by a longitudinally extending sloping hopper sheet, inner and outer side walls, and a swinging door extending on an axis transversely of the car; said outer wall sloping downwardly and inwardly from the vertical towards the longitudinal center of the car; a lever pivotally mounted on the door and having an end extended beyond the sloping side wall; and a bracket secured to the sloping side wall, with the body portion thereof disposed substantially in parallelism with the said side wall, said bracket having a shoulder formed thereon with which the projecting end of the lever is adapted to engage, said shouldered portion being offset with respect to the main body portion of the bracket to dispose it substantially tangent to the arc described by the lever at the initial movement of the bar.
20. In a dump car, the combination with means providing a hopper opening, and door means for closing said opening, locking elements mounted on one of said means in spaced relation, certain of said locking elements being disposed adjacent the side wall of the car, and other of said locking elements being disposed inwardly of said side walls; and an angular member on the other of said means, said member being arranged to initially engage the inwardly disposed locking elements on said other means to lock the door when closed, continued movement of said locking member causing the same to engage the outer of said locking elements.

In witness that I claim the foregoing I have hereunto subscribed my name this 29th day of April, 1925.

ARGYLE CAMPBELL.
